E. H. ANGLE,
VEHICLE WHEEL,
APPLICATION FILED OCT. 30, 1915.

1,179,992.

Patented Apr. 18, 1916.

FIG. 1.

FIG. 3.

FIG. 2.

FIG. 4.

UNITED STATES PATENT OFFICE.

EDWARD H. ANGLE, OF NEW LONDON, CONNECTICUT.

VEHICLE-WHEEL.

1,179,992.

Specification of Letters Patent. Patented Apr. 18, 1916.

Application filed October 30, 1915. Serial No. 58,771.

To all whom it may concern:

Be it known that I, EDWARD H. ANGLE, a citizen of the United States, and a resident of New London, in the county of New London, State of Connecticut, have invented 5 certain new and useful Improvements in Vehicle-Wheels, of which the following is a specification, reference being had to the accompanying drawings.

10 My invention relates particularly to wheel hubs, and is especially directed to the means for adjusting the hub-cap which closes the outer end of the hub.

The principal objects of my invention are, 15 to provide a wheel hub-cap with means for effecting its adjustment to the hub, which is not visible from exterior observation of said hub.

Other objects of my invention are, to provide 20 a wheel hub-cap with means for effecting its adjustment to the hub, which is so disposed as to afford the greatest possible leverage without marring said cap.

Specifically stated, my invention comprehends 25 means for the engagement of a spanner wrench with the inner wall of said wheel hub-cap, whereby said cap may be rotated in threaded engagement with the hub end, without visibly marring said cap.

30 My invention also includes all of the various novel features of construction and arrangement hereinafter more definitely specified.

In the accompanying drawings, Figure 1 35 is a side elevational view of a wheel having its hub provided with a cap constructed in accordance with my invention; Fig. 2 is an enlarged fragmentary edge elevational view of the wheel shown in Fig. 1, having a portion 40 of the hub and the cap shown in section for convenience of illustration, the section being taken along the axis of rotation of said hub; Fig. 3 is an enlarged inner face view of the cap, with a spanner wrench 45 shown in dot and dash lines operatively engaged therewith; and Fig. 4 is a perspective view of the spanner wrench for effecting the adjustment of said cap.

In said figures, the wheel comprises the 50 spokes 5, radiating from between the inner and outer hub flanges 6 and 7 respectively, the latter having the outwardly projecting barrel 9 into which the axle 10 of the vehicle extends, and within which the hub retaining 55 nut 12 may be disposed. The outer end of the hub barrel 9 may be internally threaded,

as shown in Fig. 2, to receive the externally threaded boss 13 of the hub-cap 15, which is preferably hollow, as shown, and which is provided with a plurality of recesses 16 60 extending into the body thereof from the inner surface 17, and preferably as near to the periphery thereof as may be practicable. The recesses 16 afford convenient means for turning the hub-cap 15 to adjust it into engagement with the hub barrel 9, so as to engage its shoulder 18 with the end of the hub barrel 9, or to remove it therefrom when it is desired to manipulate the nut 12 or to obtain access to the interior of said hub barrel. 65 Such adjustment of the hub-cap 15 may be conveniently effected by a spanner wrench of the type shown in Fig. 4, which comprises the handle 19 having the bifurcated semi-circular end forming arms 20 70 which are arranged to embrace the hub barrel 9, and which are provided with the studs 22 respectively arranged to engage diametrically opposite recesses 16 in said hub-cap 15. 75

It may be here noted that hub-caps as usually constructed have their outer wall provided with a polygonal recess or projection, or have their peripheral wall so formed as to be engaged by a suitable key 80 or wrench, for the purpose of rotating said cap into and out of engagement with the hub barrel, and that the effect is to mar the enameled or polished surfaces which are exposed to view. 90

My invention is advantageous in that the wrench engaging recesses are not only so disposed as not to be exposed to view, but may be so near the periphery as to afford great leverage for its rotation by the type 95 of spanner wrench shown. Furthermore, by providing the hub-cap with its means of adjustment in the inner wall thereof, desirable space is afforded on its outer surface for trade emblems, monograms, etc., as indicated 100 in Fig. 1.

I do not desire to limit my invention to the precise details of construction and arrangement herein set forth, as it is obvious that various modifications may be made 105 therein without departing from the essential features of my invention as defined in the appended claims.

Having thus described my invention, I 110 claim:

1. A vehicle hub having a threaded hub barrel, and a threaded hub-cap having re-

cesses in its inner wall affording means for effecting the threaded adjustment of said hub-cap with respect to said hub barrel.

2. A vehicle hub having a threaded hub barrel, and a threaded hub-cap having recesses in its inner wall adjacent to the periphery thereof, affording means for effecting the rotation of said hub-cap with respect to said hub barrel.

10 3. A vehicle hub having a threaded hub barrel, and a threaded hub-cap having a shoulder arranged to engage the end of said hub barrel, and having its inner wall pro-

vided with depressions whereby it may be rotated with respect to said hub barrel.

4. A cap for a vehicle hub, having its inner wall provided with recesses arranged to be engaged with a suitable tool for effecting its adjustment on said hub.

In witness whereof, I have hereunto set my hand this 28th day of October, A. D., 1915.

EDWARD H. ANGLE.

Witnesses:

NATHAN BELCHER,

WILLIAM BELCHER.
